(No Model.)

C. L. FLEISCHMANN.

SEWING MACHINE.

No. 380,317.

Patented Apr. 3, 1888.

UNITED STATES PATENT OFFICE.

CHARLES LOUIS FLEISCHMANN, OF WASHINGTON, DISTRICT OF COLUMBIA.

SEWING-MACHINE.

SPECIFICATION forming part of Letters Patent No. 380,317, dated April 3, 1883.

Application filed April 5, 1887. Serial No. 233,809. (No model.)

To all whom it may concern:

Be it known that I, CHARLES LOUIS FLEISCHMANN, a citizen of the United States, residing in Washington, in the District of Columbia, 5 have invented a new and useful Improvement in Sewing-Machines, of which the following specification is a full, clear, and exact description.

My invention relates to mechanism for moving the needle-bar and shuttle.

The invention, stated in very general terms, consists, first, in a reciprocating shuttle-carrier combined with a star-wheel or many-armed lever and connections with the needle-bar, 15 whereby the needle is properly reciprocated to carry the thread through the cloth, make the loop to receive the shuttle-thread, and then tighten said loop to finish the stitch.

In the accompanying drawings, in the several figures of which like parts are similarly designated, Figure 1 is a perspective view of the machine applied to one corner of a table. Fig. 2 is a rear end elevation of the machine on a larger scale. Fig. 3 is a plan view. Fig. 25 4 is a side view of the shuttle-carrier in its rearmost position, and Fig. 5 is a similar view in its foremost position.

The head of the machine, the presser-foot, the shuttle, and the feed may be of any approved construction. The bed-plate A is provided with a suitable number of legs, *a a*, and may be provided with a clamping device, *A'*, for securing the machine to the table.

B is the neck, having the head *B'*, which receives the presser-foot bar *B''* and needle-bar *B''*. The bed-plate A is provided with the rearwardly-extending arms *A''*, which form journals for the shaft *D D'*, the cranked end of the shaft being designated *D*. On this shaft is 40 arranged a band wheel or pulley, *C*.

Suitably supported in the bed A is a slide, *F*, herein referred to as the shuttle-carrier, the shuttle being arranged in any suitable manner in the forward end of the said slide. This 45 slide is given a reciprocating motion by means of a link, *E*, connecting it to the crank *D*, which crank, as will appear presently, has a rotary motion imparted to it. The shuttle-carrier *F* is provided with a series of pins or studs, *G H I*, projecting laterally from one face thereof, and these pins are engaged, in the manner hereinafter more particularly set forth, by the star-

wheel or many-armed lever *N*, pivoted to the arm *B*, this lever being in turn connected by a slotted link or rod, *O*, with the lever *M*, the last-named lever, *M*, being pivoted to the arm *B* and loosely jointed to the needle-bar *B''*.

As the driving mechanism I may employ a treadle, *R*, arranged upon a treadle-stand, *R'*, which may be suitably secured to the floor, the 60 said treadle-stand having projecting from and hinged to it a frame, *R''*, in which is journaled a wheel, *U*. This wheel *U* is connected by a pitman, *R''*, with the treadle *R* in any ordinary manner of driving a wheel by means of 65 the pitman and treadle. A band, *S*, extends from the wheel *U* to the wheel *C*. Hooks *T*, hinged to the frame *R''*, are adapted to be engaged with lugs *C' C''*, projecting laterally from the arms *A'' A''*, whereby the said driving-frame 70 is supported from the machine-bed. By hinging together the parts of the driving mechanism it may be folded together very compactly for transportation and storage.

The operation is as follows: Rotary motion 75 being given to wheel *U* by means of the treadle *R* and the connecting-pitman *R''*, the belt transmits said motion to the pulley *C*, and it in turn rotates the crank-shaft *D D'*. This motion of the crank-shaft imparts a reciprocating motion 80 in a right line to the shuttle-carrier *F*, through the medium of the link *E*. When the shuttle-carrier is drawn in the direction of the wheel *C*, the shuttle is placed somewhat beyond the needle, so that the point of the shuttle 85 comes close to the needle-loop, while the stud or pin *H* pushes back the arm *b* of the wheel or lever *N*. This motion raises the arm *c* of said wheel or lever *N*, and of course it presses down the curved arm *d* of said lever or 90 wheel. By this motion the connecting-rod *O*, which is jointed to the arm *c*, is raised and forces down the needle-bar through the lever *M*, so as to cause the needle to penetrate the goods. By this time the shuttle-carrier has 95 finished its backward movement, and now begins its return-stroke. On this return-stroke the shuttle-carrier has a lost motion of about two inches before the stud *G* comes in contact with the arm *b*, so that the stud *G* has time to 100 move out from under the arm *d*, thereby drawing down the rod *O* and the lever *M*, and partly elevating the needle-rod to form the thread-loop. As soon as the stud *G* is free from the

arm *b*, the shuttle enters the loop and at that moment the stud *I* engages the arm *b* and causes the lever *M* to draw the needle from the goods and finish the stitch, and at this time 5 the shuttle-carrier is again withdrawn, ready to go through the same motions again. The slot *P*, in the connection of the link *O* with the lever *M*, gives the necessary slack motion to permit the formation of the thread-loop.

10 What I claim is--

1. In a sewing-machine, a reciprocating needle-bar and needle, and a reciprocating shuttle, combined with a shuttle-carrier provided with studs or pins *G H I*, and a many-15 armed lever engaged by said studs or pins, and

connections between the said lever and needle-bar to operate the latter, substantially as described.

2. In a sewing-machine, a reciprocating needle-bar, a reciprocating shuttle-carrier provided with laterally-projecting studs, and a many-armed lever having one of its arms bent and co-operating with said studs, and connected with the needle-bar to impart the usual dip to the needle-bar, so as to form the loop 20 in the needle-thread, substantially as described. 25

CHARLES LOUIS FLEISCHMANN.
